UNITED STATES PATENT OFFICE.

EGBERT H. GOLD, OF CHICAGO, ILLINOIS.

MULTIPLE-REGULATION HEATING SYSTEM.

987,569.

Specification of Letters Patent. Patented Mar. 21, 1911.

Application filed June 7, 1909. Serial No. 500,480.

To all whom it may concern:

Be it known that I, EGBERT H. GOLD, a citizen of the United States, residing at Chicago, in the county of Cook and State 5 of Illinois, have invented certain new and useful Improvements in Multiple-Regulation Heating Systems, of which the following is a specification.

My invention relates to an automatically 10 regulated heating system intended or designed particularly for heating railway cars which are so constructed or which are used under such conditions that it is desirable that there should be an arbitrary regulation, 15 of considerable range, of the amount of radiating surface under steam at any one time, in addition to the automatic regulation of the supply of steam to the radiating coils to maintain a uniform pressure in the 20 coils in use. It is especially desirable to employ a heating system of this character in steel passenger cars and particularly in cars of this construction which have to make long trips through open and sunny country 25 or through territory where, for any reason, there is a very considerable change in temperature between day and night. In cars of steel construction, the temperature inside the cars responds very quickly to changes 30 in outside temperature, this being due, of course, to the fact that steel is a very good conductor of heat. The result is that the amount of variation in heat imparted by 35 an automatically controlled system of heating may not be adequate, under some conditions, in cars of this construction, to meet the requirements and to maintain at all times the desired temperature in the car. Thus, in mild weather, the sunny side of 40 such a car is apt to be extremely warm because of the freedom with which the heat of the sun, striking the metal side of the car, is conducted to the interior of the car, while the opposite side of the car in the 45 shade may be sufficiently cool, for similar reasons, to make it desirable to have some slight artificial heat on that side. On the other hand, in very cold weather the free 50 radiation of heat from the interior of the car through the metal sides of the car may result in such a rapid cooling of the car that a radiating surface in the heating system which would ordinarily be sufficient to comfortably heat the car when the system

is supplied with steam at atmospheric or 55 low pressure would be inadequate to keep the car comfortably warm.

The object of the invention is to provide a suitable heating system for cars of this description and, generally speaking, to provide a heating system for any cars in which the amount of radiating surface under steam may be widely and exactly varied, the automatic regulation of supply being maintained for whatever radiating surface is used; and 60 to accomplish this result by apparatus which is simple and does not involve undue multiplication of valves and controllers, whereby heating apparatus is provided which will be relatively inexpensive to install and 65 maintain and will be easily comprehensible, as to its operation, to the attendant having charge of the same.

While the arrangement of coils, valves 75 and controllers forming the subject-matter 75 of this invention might be employed in various different heating systems, the arrangement is of particular advantage when forming a part of an atmospheric pressure or vapor system of heating in which a uniform pressure is maintained in the radiators, regardless of changes in pressure in the train pipe and regardless of changes in 80 the weather. In such a system there is no strong steam pressure to force the steam 85 into the empty pipes and to drive out cold air and water of condensation, and consequently the tendency of the low pressure steam to follow the path of least resistance 90 is greatly emphasized.

In this regard it is one of the objects of my invention to adapt the vapor system to the heating of railway cars under the conditions aforementioned, although it should be understood that my invention is not 95 necessarily limited to use in such a system.

The invention has for further objects such new and improved constructions, arrangements and devices in car heating systems as will be described in this specification and 100 particularly set forth in the claims appended thereto.

The invention in a preferred embodiment is illustrated in the accompanying drawings, wherein—

Figure 1 is a sectional plan view of a car illustrating an application thereto of my heating system, the heating coils, how-

ever, being arranged conventionally for the purpose of clearness of illustration. Fig. 2 is a sectional plan taken through two of the four-way valves used in the system. Fig. 3 is a section on line 3-3 of Fig. 2, looking in the direction of the arrows. Fig. 4 is a sectional view of the vapor regulator; and Fig. 5 is a transverse section of the car showing the actual arrangement of the radiating coils and certain of their connections.

Like characters of reference indicate like parts in the several figures of the drawings.

Referring to the drawings, A represents a railway car of ordinary construction, and B the steam train pipe which runs the length of the train and is kept filled with steam from the locomotive at relatively high but varying pressures. Fig. 20 The car is heated by a plurality of radiators, or radiator units, shown, for convenience, as two on each side of the car. These radiators are shown in their actual position in Fig. 5; in Fig. 1 they are arranged conventionally in horizontal position for the purpose of including in this view all of the instrumentalities employed in the heating system. On one side of the car is a radiator C and a radiator D, the former of these 30 consisting, as shown, of three pipes, the latter of two, so that the amount of radiating surface of the two coils stands in the ratio of three to two, although this particular ratio is not essential. There are two 35 corresponding coils C', D' on the opposite side of the car.

Preferably all the coils on one side of the car are controlled by a single vapor regulator, the two vapor regulators being designated E, E'. Coils C and D are connected together and with the vapor regulator E by means of the four-way valves F and G; coils C' and D' being similarly connected by similar valves F' and G'. A suitable 45 form of vapor regulator is shown in Fig. 4, although any other device for regulating the inflow to the coils in accordance with thermostatic conditions in proximity to their outlet might be employed. Inasmuch as the 50 radiating pipes on one side of the car extend through substantially the same space, and receive their supply of steam from the same supply circuit, composed of the pipes 41 and 42 having the valves F, G interposed 55 therein and controlled by a single automatic controller which is common to all of the units of one set, it will be seen that the pipes on one side of the car constitute virtually a single radiator composed of a plurality of units so arranged, as hereinafter explained, that any one or more of the units 60 may be in operation at the same time to heat the same space.

Referring particularly to Fig. 4, the vapor 65 regulator is formed with a casing 10 divided

by a partition 11 into high pressure chamber 12 and low pressure chamber 13, which communicate by means of a port 14 closed by a valve 15 on a stem 16, connected with a bell crank 17. A casing forming a thermostat chamber 18 contains the thermostat 19 and its operating rod 20, the latter being connected with bell crank 17. As this form of vapor regulator is well known, I have only referred to such parts as are necessary for a proper understanding of the present invention. Fig. 4 shows vapor regulator E. The other vapor regulator E' is of identical construction.

The construction and arrangement of one set of four-way valves are shown in Figs. 2 and 3. These devices comprise each a casing 21 divided by webs 22, 23, 24, 25 into compartments 26, 27, 28 and 29. Between the webs is a valve piece consisting of an upper disk 30, a lower disk 31 and a vertical web 32 said valve piece having a stem 33, provided with a handle 34, a spring 35 being interposed between the bonnet 36 of the valve and the upper disk 30. The lower disk is perforated at 37 and the bottom of the casing 21 at 38, these two perforations registering when the web 32 is turned to the dotted line position of Fig. 2 and forming a drip outlet for the short circuited radiator. A short pipe 39 connects the train pipe B with the high pressure chamber 12 of the controller; a pipe 40 the low pressure chamber 13 of the controller with compartment 26 of valve F; a pipe 41 compartment 26 of valve 10 27 of valve F with compartment 26 of valve G; a pipe 42 compartment 27 of valve G with thermostat chamber 18 of the controller. The inlet end 43 of coil C leads from compartment 29 of valve F and the return end 10 44 of this coil to compartment 28 of the same valve. Similarly the inlet end 45 of coil D leads from compartment 29 of valve G and the return end 46 of the coil to compartment 28 of this valve. It will be understood that the arrangement will be the same on the other side of the car.

The operation of the heating system as above described is as follows: Considering the arrangements on both sides of the car, the car is provided with four heating coils, two of which are of greater radiating surface than the other two. This difference may result either from the use of more pipes in one case than the other or the use of larger pipes or of pipes of greater length. When the ratio between the radiators of greater and of less capacity is three to two, it is obvious that, by making different combinations, an arbitrary regulation of heat is obtained, whereby either twenty, thirty, forty, fifty, sixty, seventy, eighty or one hundred per cent. of the maximum is obtainable, as may be desired. The automatic regulation responds to this arbitrary regu- 1

lation, that is, just enough steam is supplied to the coil or coils in service to make up for loss by condensation, and keep the coil or coils full of steam at the predetermined pressure. Supposing that it is desired to obtain only twenty per cent. of the maximum amount of heat obtainable from the system, valve F will be set to its dotted line position (Fig. 2), short circuiting coil C, and valve G will be in its full line position, so as to admit steam to coil D which, in the assumed case, has twenty per cent. of the entire radiating surface of the system. The steam flows from train pipe B past valve 15, supposing this to be open, through compartments 26, 27 of valve F, pipe 41, compartments 26 and 29 of valve G, thence through coil D, compartments 28 and 27 of valve G and then through pipe 42 into contact with the thermostat 19. The contact of steam with the thermostat expands the same, closing or partially closing supply valve 15. The flow of steam to the thermostat thereupon ceasing, the thermostat soon cools and contracts, re-opening supply valve 15. Supposing that it is desired to obtain thirty per cent. of the maximum heat obtainable from the system, the position of valves F and G will be reversed. If forty per cent. is needed, coil D will be put in service in conjunction with coil D' on the opposite side of the car, the use of the latter bringing into operation thermostat E' and valves F' and G'. To run the system at fifty per cent. of its full capacity, valves F and G will be in their full line positions and in this case, it will be observed, coils C and D are connected up in series, so that steam is obliged to pass through coil C before it can reach coil D and through both of them before it comes into contact with the thermostat. By this arrangement, the short circuiting of any coil is prevented. If the coils were arranged, for example, so that both are fed independently from a common source, the steam would naturally follow the course of least resistance, that is, go through the shorter coil or the hotter coil, and so interfere with the accuracy of regulation of the system. This is especially important when low or atmospheric pressure steam is used. The system will operate at sixty per cent. capacity with coils C, C' in service and the others cut out; at seventy-five per cent. with coil C and coils D, D' in service; and at eighty per cent. with all but one of the shorter coils receiving steam.

It will be seen that I provide in a system in which the regulation of the steam is primarily automatic an arbitrary regulation of very considerable range and flexibility, and accomplish this desirable result by apparatus which is comparatively simple, involving the duplication of but a few parts, with only the usual number of automatic

regulators, and easily comprehended in its operation by the attendant having charge of the same.

While I have shown an arrangement of two coils on each side of the car, it is obvious that a greater number of coils might be employed, although in practice a sufficient range of regulation may be obtained by using in all two short coils and two long coils in the manner shown. When any radiator is short circuited, an outlet for the water of condensation is provided by the perforations 37 and 38.

I do not limit myself to the particular devices, constructions and arrangements shown, as modifications might be devised that would come within the scope of my invention as defined by the claims. I do not claim in this application the arrangement *per se* of two heating coils in parallel connected by four-way valves, so that either or both coils may be supplied with steam, as desired, nor the serial connection between the coils when both are in service, as that arrangement is broadly claimed in my co-pending application Serial No. 500,477 filed June 7, 1909, this application being limited to the employment of radiators consisting of radiating units having different heating capacities, substantially as described.

I claim:

1. The combination with a railway car, of a radiator arranged at one side of the car and consisting of a plurality of units of different radiating surfaces, a supply circuit common to all of said units, a source of supply of heating medium with which said supply circuit communicates, means arranged to be actuated by the heating medium in the supply circuit to automatically control the supply of the heating medium to said supply circuit, and a plurality of four-way valves arranged in series in said supply circuit, each of said units communicating at its supply and return ends with one of said four-way valves, whereby heating medium may be supplied at will to any one of said units or may be caused to flow serially through any two or more of said units, the opposite side of the car being provided with a similar arrangement whereby the temperature of the car and of the different sides thereof may be controlled and varied at will.

2. The combination with a railway car comprising an apartment, of a train pipe carrying a supply of steam at high but variable pressures, a radiator in said apartment consisting of a plurality of radiating units, said radiating units having different amounts of radiating surface, a common controller for said units which is adapted to maintain steam in said radiator at a definite pressure, whether all or less than all of said units are under steam; and means for varying the amount of heat delivered to the

apartment by said radiator comprising separate valve devices for the several units, each of which has a single operating member, said devices being adapted at one position of their operating members, to admit steam to their respective units, each independently of the other, and at the other positions of said operating members to shut off steam from said respective units, independently of each other; said valve devices being so arranged that when steam is circulated through more than one unit it is compelled to pass through such several units in series.

3. The combination with a railway car, of a train pipe carrying steam at high but variable pressure, a radiator on each side of said car and extending through the same compartment thereof comprising in each case two radiating coils, the different coils of each radiator having different capacities, of a supply pipe leading from the train pipe to each radiator; discharge pipes leading from said radiators having free discharge to the atmosphere; a four-way valve associated with each of said radiating coils, the four-way valve of one of said coils of each radiator being adapted either to put into communication with each other the supply pipe of

said radiator and the inlet end of said coil, 30 and the outlet end of said coil and four-way valve of the other coil of said radiator, and at the same time to close direct communication between said supply pipe and the four-way valve of the said other coil; or to close 35 the inlet and outlet ends of its said coil and open direct communication between the supply pipe and the four-way valve of said other coil; the other four-way valve being adapted either to put the inlet end of its coil 40 into communication with said first mentioned four-way valve and the outlet end into communication with the discharge pipe of said radiator, closing direct communication between the first mentioned four-way valve 45 and the discharge pipe; or, to close the inlet and outlet ends of its said coil and to open communication between the first mentioned four-way valve and said discharge pipe; and thermostatic means operated in accordance 50 with the thermostatic condition of the medium in said discharge pipe for controlling the flow of steam from said train pipe to such of said coils as are supplied with steam.
